UNITED STATES PATENT OFFICE

ROBERT K. WINNING, OF WAUWATOSA, WISCONSIN, ASSIGNOR, BY MESNE ASSIGNMENTS, TO DUDLEY LOCK CORPORATION, OF CHICAGO, ILLINOIS, A CORPORATION OF ILLINOIS

PERMUTATION LOCK

Application filed January 28, 1929. Serial No. 335,511.

This invention relates to improvements in permutation locks.

It is the object of the invention to provide a permutation lock having an improved snap action whereby each operative position of the selector knob is definitely, while impositively, made apparent to the touch of the operator and is also rendered audible, the point of origin from which the angular position of the selector is determined being tangibly distinct from all other positions thereof.

It is particularly my purpose to achieve these results in novel and simple form and at greatly reduced cost of manufacture as compared with any other devices for defining the positions of this type of lock.

In the drawings—

Figure 1 is a front elevation of a padlock embodying permutation mechanism made in accordance with this invention;

Figure 2 is an axial section through the lock shown in Figure 1.

Like parts are identified by similar reference characters throughout the several views.

The lock casing 5 contains the usual permutation disks 6 and 7 between which the spacers 8 may be disposed and with which the keeper 9 may be associated for the control of shackle 10 in the manner specifically described in my Patent No. 1,655,002, dated January 3, 1928. The present invention relates more particularly to the selector knob 15 and its relation to the front wall 16 of the lock casing.

It will be observed that the knob 15 is reduced in diameter at 17 to provide a shoulder 18 beneath which is engaged a stamped disk 19 carrying a pointer 20 which moves with the knob as the knob is rotated.

The portion 17 of the knob passes through an aperture in the front wall 16 of the lock casing and is provided therein with a portion 21 further reduced in diameter to provide a shoulder 22. The reduced portion 21 of the knob is channeled at 23 to provide longitudinally extending grooves within which integral tongues of tumbler 7, washer 24, and spring 25 are engaged whereby these parts are all keyed to the knob for rotation

therewith. The reduced portion of the knob is upset at 26 to bind the parts permanently together in the manner above indicated.

It will be noted that the front wall 16 of the lock casing is outwardly bowed or dished so that the interior surface thereof is concave. The front wall is embossed to provide an elongated boss at 30 and a series of substantially circular bosses 31 corresponding in number to the several positions of the permutation mechanism and distinguished from boss 30, the point of origin, in form whereby the difference will readily be apparent to the touch, even in the dark.

The flat spring 25 when bound upon shoulder 22 by the riveting operation conducted upon the knob 26 is forced to assume a convexity corresponding to the form of the outer wall 16 of the lock casing. Its extremities are thus placed under resilient pressure in the direction of the front wall, and the bosses 32 formed in the ends of spring 25 are yieldably urged into registry with the interiors of bosses 30 and 31 in the several effective positions of the knob 15. These parts co-operate with a distinct snap action to provide a yieldable detent which impositively but nevertheless very tangibly defines each potential operative position of the permutation parts as determined by the knob. The interaction of bosses 32 of the spring with boss 30, of the front wall 16, of the lock casing, is exactly the same as the interaction of boss 32 with bosses 31 since the circumferential dimension of boss 30 is substantially the same as the corresponding dimensions of bosses 31. To the operator, however, boss 30 is different not only in appearance but also to the touch.

The pointer 20 is so attached to knob 15 that it points directly to the particular boss of the casing in which one of the spring bosses 32 is engaged. This is not essential but it is desirable that in each position defined by the detent structure the pointer should be directed precisely to one of the exteriorly apparent bosses on the casing. For convenience, the bosses 31 may be numbered but their numbering is not essential for the reason that the distance of the point-

er from the point of origin 30 may readily be ascertained in any operation of the lock both tangibly and audibly due to the snap action of the detent device.

5. It is particularly to be observed that the pointer 20 is relatively short. This is desirable in order that the operator may readily feel the distinction between boss 30 and bosses 31. If the pointer were long enough 10 to extend to the arc in which bosses 31 are disposed, it would cover a major portion of boss 30 and would thereby conceal the difference intentionally established between boss 30 and bosses 31.

15. I claim:

1. A permutation lock comprising a casing having a front wall outwardly embossed at predetermined stations, a knob rotatable with respect to said wall, and a spring connected with said knob for rotation therewith and provided with diametrically opposite parts arranged for substantially balanced interaction at said stations with the outwardly embossed portions of said wall.

25. 2. In a permutation lock the combination with a lock casing having a front wall outwardly embossed at predetermined stations, of a knob rotatable with respect to said wall, permutation mechanism controlled by the rotation of said knob, and a detent member carried by said knob within said wall and provided with a resiliently mounted boss arranged to interact with the bosses of said 30 wall in the predetermined stations of said 35 knob.

3. In a permutation lock the combination with a lock casing having a front wall outwardly embossed at predetermined stations, of a knob rotatable with respect to said wall,

40. permutation mechanism controlled by the rotation of said knob, and a detent member carried by said knob within said wall and provided with a resiliently mounted boss arranged to interact with the bosses of said 45 wall in the predetermined stations of said selector, said knob being provided externally of said wall with a pointer mounted thereon to register angularly with one of the bosses of said wall at each station to which said

50. knob is adjusted, whereby said wall bosses indicate the position of said knob visibly in conjunction with said pointer and tangibly in conjunction with said detent member.

4. In a device of the character described, 55 the combination with a casing having a front wall provided with bosses at predetermined stations in arcuate series, a selector knob rotatable with respect to said wall and having portions interiorly and exteriorly disposed with reference thereto, a detent member carried by said knob within said wall and provided with means resiliently co-acting internally with the bosses of said wall, a pointer carried by said knob exteriorly of said wall and arranged to designate

one of the bosses of said wall in each position of co-action of said detent member therewith, and means upon said knob binding said detent member and pointer upon said wall at opposite sides thereof.

5. In a device of the character described, the combination with a casing having a front wall provided with bosses at predetermined stations in arcuate series, a selector knob rotatable with respect to said wall and having portions interiorly and exteriorly disposed with reference thereto, a detent member carried by said knob within said wall and provided with means resiliently co-acting internally with the bosses of said wall, a pointer carried by said knob exteriorly of said wall and arranged to designate one of the bosses of said wall in each position of co-action of said detent member therewith, and means upon said knob binding said detent member and pointer upon said wall at opposite sides thereof, said means comprising a riveted internal extremity of said knob.

6. In a device of the character described, the combination with a casing having a front wall provided with bosses at predetermined stations in arcuate series, a selector knob rotatable with respect to said wall and having portions interiorly and exteriorly disposed with reference thereto, a detent member carried by said knob within said wall and provided with means resiliently co-acting internally with the bosses of said wall, a pointer carried by said knob exteriorly of said wall and arranged to designate one of the bosses of said wall in each position of co-action of said detent member therewith, and means upon said knob binding said detent member and pointer upon said wall at opposite sides thereof, said means comprising a riveted internal extremity of said knob.

7. In a device of the character described, the combination with a casing having a front wall outwardly embossed at predetermined stations and in arcuate series, said wall being outwardly bowed of a selector knob rotatable in said wall and a spring detent connected with said knob and held thereby adjacent a central portion of said wall whereby the extremities of said detents are forced into engagement with said wall adjacent said series of bosses therein, and means carried by said spring detent for interaction with said bosses.

8. In a device of the character described, the combination with a lock casing and permutation mechanism therein, the front wall of said casing being provided with substantially spherical bosses in arcuate series, and a distinctive radially elongated boss at one point in said series, of a knob ro-

tatable in said wall and operatively associated with said permutation mechanism within said lock, and a pointer carried by said knob and arranged to designate the several bosses of said series in the course of rotative adjustment of the knob, said pointer being sufficiently short to permit the elongated form of said distinctive boss to be tangibly apparent.

9. In a device of the character described, the combination with a lock casing and permutation mechanism therein, the front wall of said casing being provided with substantially spherical bosses in arcuate series, and a distinctive radially elongated boss at one point in said series, of a knob rotatable in said wall and operatively associated with said permutation mechanism within said lock, and a pointer carried by said knob and arranged to designate the several bosses of said series in the course of rotative adjustment of the knob, said pointer being sufficiently short to permit the elongated form of said distinctive boss to be tangibly apparent, together with detent mechanism connected with said knob within said wall and co-acting internally with said bosses in positions of registry of said pointer externally therewith.

10. In a device of the character described, the combination with a lock casing and permutation mechanism therein, the front wall of said casing being provided with substantially spherical bosses in arcuate series, and a distinctive radially elongated boss at one point in said series, of a knob rotatable in said wall and operatively associated with said permutation mechanism within said lock, and a pointer carried by said knob and arranged to designate the several bosses of said series in the course of rotative adjustment of the knob, said pointer being sufficiently short to permit the elongated form of said distinctive boss to be tangibly apparent, together with detent mechanism connected with said knob within said wall and co-acting internally with said bosses in positions of registry of said pointer externally therewith, said detent mechanism comprising a flat spring secured to said knob and provided with bosses complementary to the bosses of said wall.

ROBERT K. WINNING.
